COIN SELECTING MECHANISM

Charles W. McKee, Seattle, Wash., assignor to
McKee Coin Selector, Inc., a corporation of
Washington

Application July 30, 1934, Serial No. 737,542

11 Claims. (Cl. 194—97)

This invention relates to coin or token selecting mechanisms and it has reference more particularly to a means for use in connection with coin controlled machines for rejection of all coins, tokens and slugs inserted therein except those which it is intended shall be used in the machine. The principal object of this invention resides in the provision of a mechanism whereby the configuration of a coin is utilized to actuate any suitable mechanism for separating the valid or predetermined type of coin from spurious ones.

It is also an object of the invention to provide means whereby coins, tokens, or the like, of a designated kind are selected by means of their particular surface irregularities.

More specifically stated, the present invention resides in the provision of a machine of the above stated character having a coin chute and means associated therewith for retaining each inserted coin in position for identification by a plurality of feelers which, if brought into a certain predetermined relationship, possible only when simultaneously in contact with the irregular surface of the particular coin which it is intended shall be used, will effect the opening of a gate in the chute to deliver the coin, when subsequently released, into the machine.

Another object of the invention resides in the provision of a novel means for supporting the coin and for rotating it in contact with the feelers in making the identifying test.

Other objects of the invention reside in the details of construction of means whereby an operation of the handle of the identifying machine cannot be made except when a coin is inserted and other means whereby an operation with the coin inserted cannot be partially made.

Other objects reside in the details of construction and combination of parts and in their mode of operation, as will hereinafter be fully described.

In accomplishing these and other objects, I have provided the improved details of construction, the preferred forms of which are illustrated in the accompanying drawings, wherein—

Fig. 1 is a cross sectional view of the machine with parts in position for reception of a coin.

Fig. 2 is a similar view showing the parts set for inspection of a coin.

Fig. 3 is a cross sectional detail on line 3—3 in Fig. 1.

Fig. 4 is a cross section on line 4—4 in Fig. 2.

Fig. 5 is a fragmental view of the pawl and ratchet mechanism.

Figs. 6, 7, and 8 are views of the coin in different positions during a test.

Fig. 9 is a diagrammatic view of a device of an alternative type of construction utilizing an electrically controlled mechanism.

Fig. 10 illustrates in side elevation another form of device.

Fig. 11 is a back view of the same.

Referring more in detail to the drawings—First, describing the construction as disclosed in Figs. 1 to 8, inclusive—

1 designates a boxlike housing in which the coin testing, or identifying, mechanism is contained. Leading vertically through the housing is a coin chute 2 with its upper end opening 15 through the top wall of the housing in a flared mouth 3. This chute extends down through the bottom wall of the housing into the mechanism, not herein shown, which is to be operated or controlled by the coin and which might be a 20 telephone, vending machine, or the like.

Within the housing the chute is provided with a diverting gate or valve 4 pivotally mounted by a supporting shaft 5 at its lower end and movable thereby to open and closed positions. In its normal position, as seen in Fig. 1, it closes off direct passage of undesired coins of any kind or slugs through the chute 2 and diverts them into a lateral chute 6 which, in the present instance leads into a box or receptacle 7a within housing 30 1 for confiscation of the coin. When in its other position, as seen in Fig. 2, it provides direct passage through chute 2 and closes the entrance to chute 6. A lateral lever arm 7 is fixed to the gate shaft 5 and is actuated, as presently described, to move the gate between its two positions above described.

When a coin is dropped into chute 2 it is stopped at the testing station before it reaches the diverting gate 4, by coming against the end 40 portion of a horizontal lever 10 that extends into the chute. This lever 10 is so located that it will temporarily stop the coin in registration with a yieldable pad 11, as in Fig. 6, that is fixed on the inner end of a sleeve 12 that is revoluble and also 45 longitudinally movable on a supporting bolt 13 fixed in the front wall of the housing. The sleeve has a counterbore 12a in its inner end underlying the gripping pad 11 and a coiled spring 14 surrounds the bolt and bears against the base portion of the counterbore and against the bolt head 13a to yieldingly urge the sleeve toward the front of the housing and thereby hold the pad 11 at a position out of the chute so that the coin 55

may be received on the lever 10 alongside of the pad, as shown in Fig. 6.

For the purpose of testing, or inspecting, the coin, it is rotated axially by the pad while a plurality of feelers are held in contact with one surface thereof. Rotation of the coin is effected by axial rotation of the sleeve 12 while the pad 11 is held pressed against the coin by means presently described; it being understood that the pad 10 being of yieldable material will frictionally grip the coin when pressed thereagainst.

The feelers consist of a plurality of independently movable pins 15 that are slidably movable in a supporting block 16 fixed to the side of chute 2 opposite the pad 11. The inner rounded ends of these pins are adapted to bear directly against the adjacent surface of a coin C that is held in testing position, as shown in Figs. 7 and 8 and while the coin is being rotated by the pad 11. At their outer ends the pins 15 are pivotally connected, respectively, as at 17, with the lower ends of levers 18 which, in turn, are pivotally fixed at points near their lower ends, as at 19, to the ends of supporting brackets 20 that extend from the block 16. Springs 21 are attached to the levers 18 above the pivots 19 and to the housing in a manner to cause the inner ends of the pins 15 to be urged against the coin held in testing position. Thus it is apparent that irregularities in that surface of the coin against which the feelers press, will, upon rotation of the coin, cause the feelers to be moved inwardly or outwardly accordingly, and their movement will cause an inward or outward swinging of the upper ends of levers 18.

Each lever 18 is pivotally attached at its upper end to a horizontally disposed bar 24. These several bars are slidably movable in a bracket 25 supported by an arm 26 from the block 16. Each bar 24 is provided in its top edge with a notch 27, as shown in Fig. 1. A lever arm 28 is pivoted at one end on the arm 26, as at 29, and has its opposite end portion overlying the three bars 24 and has a link 30 connecting its movable end with the arm 7 for actuating the gate 4 when the bars 24 are brought to such position that the notches 27 thereof will be in exact alignment beneath the lever, the lever 28 will drop downwardly therein and, by means of link 30, the gate 4 will be actuated to open position, of Fig. 2, but when the lever 28 is lifted out of the notches to rest upon the bars, as in Fig. 1, the gate 4 will be moved to closed position. Thus it is apparent that if the machine is intended to accept only coins or tokens having certain surface characteristics such, for example, as the present day buffalo nickel, the notches 27 can be so located in the bars 24 that at a certain position of the coin during its period of rotation, the feeler pins will shift the bars 24 to positions to cause the notches 27 to come into alignment and permit the lever arm 28 to drop therein; thus, to open gate 4 so that, on release of the coin from the pad 11, it will continue down the chute 2 to the machine it is intended to control. If, however, the gate 4 is not opened as would be the case if the coin was not of a proper kind, the coin when released by the pad 11 would be diverted into the box 7a and confiscated or re-70 turned without delivery to the machine to be operated.

When a coin is released by the pad 11 and passes down through chute 2 past the gate 4, it contacts with the inner end of a trip lever 30 pivoted, as at 31, and moves the outer end of the lever up-

wardly. The outer end of the lever is connected by a link 32 with the arm 7, and thus it operates to lift the link 30 to unseat the lever 28 from the notches of the bars 24 and permits the feelers to be reset under action of springs 21.

Testing of a coin is effected by rotating it while it is pressed inwardly by the pad 11 against the inner face of block 16 and with the feelers 15 bearing yieldingly thereagainst. The means for thus holding and rotating the coin is as follows—

Pivotedly attached, as at 35, to a bracket 36 fixed to the back wall of the housing is a lever 38 that extends forwardly through the housing and through a vertical slot 39 in the forward or front wall. At its outer end, the lever has a handle 40 whereby it may be actuated downwardly from position of Fig. 1 to position of Fig. 2. A cable 42 is attached to the lever and is wound about the sleeve 12 and is attached thereto so that, on depression of the lever 38, the sleeve 20 will be rotated thus to wind up a clock spring 45 contained within the outer end of the sleeve with opposite ends fixed to the sleeve and its supporting bolt 13, respectively. Also, supported on the inner face of the forward wall of the housing is a vertically movable sleeve shifting bar 50 which has a laterally turned flange 51 at its lower end formed with a vertical slot 52, as seen in Fig. 3. At its upper end the bar has a vertical slot 53 that receives the inner end of bolt 13 therethrough as a guide while a headed pin 54 extends through the lower slot 52 into the housing wall as a guide for that end. The upper end of the bar 50 has cam surfaces 50a which, upon downward shifting of the bar, will engage with the inner end of the sleeve to push the sleeve inwardly along the bolt 13 against the expanding pressure of spring 45, thereby to cause the pad 11 to press against a coin which has been inserted in the chute and is then supported by the lower end of lever 10.

Downward shifting of the bar 50 for inward actuation of the sleeve 12 is effected by means of a stud 60 fixed on a block 61 that is slidable on the lever 38. This stud projects into and is movable along a slot 63 that extends lengthwise of an outturned flange 50' of the bar 50. When the lever 38 is pushed downwardly to its lower limit for actuation of the device, the stud 60 engages with the lower end of slot 63 and causes the bar 50 to be shifted downwardly thereby to cause the cam surfaces 50a at its upper end to effect the inward shifting of the sleeve. On release of the lever 38 after being fully depressed, the clock spring unwinds, and thereby rotates the sleeve and also winds up the cable 42 and brings the lever 38 back to raised position. During final upward movement of the lever the stud 60 engages with the upper end of slot 63 and thereby shifts the bar 50 upwardly and thus disengages the cam surfaces 50a from the sleeve and the latter is shifted outwardly by spring 45 thereby causing pad 11 to release its hold on the coin so that the coin may drop down chute 2 either to the machine to be operated or diverted to the receptacle 7.

It will be explained here that when the coin is pressed inwardly by the pad 11 against the face of block 16, as shown in Fig. 2, it effects the withdrawal of the end of lever 10 from the chute so that when the coin is ultimately released, the lever 10 will not be in the way of the coin in passing down the chute. To effect this withdrawal of the lever 10, there is provided a link 55 suspended by pivotal connection, as at 56, with a bracket 57 on the block 16. A push pin 58 extends slidably

through the block to engage the coin and at its outer end is pivotally attached to link 55. Thus, when a coin is actuated laterally by pressure of pad 11 thereagainst, it pushes the pin 58 outwardly 5 and this in turn causes an outward swinging of the link 55. Lever 10 is pivotally attached to link 55, and thus its end is pulled from chute 2 to the position of Fig. 2. To hold the lever 10 in withdrawn position until the coin has been tested and 10 dropped down the chute 2, a latch lever 59 is pivoted on the block 16 and is pulled upwardly by a spring 60. When link 55 is pushed rearwardly, as in Fig. 2, it is engaged by latch 59 and is held at that position, against the inward pull of a 15 spring 61 that is attached to block 16 and to the link.

When the tested coin is released by the outward withdrawal of pad 11, it drops down the chute and engages the inner end of a lever 63 extended into the chute. This lever is connected by a link 64 with latch 59 in a manner whereby the coin in passing the lever 63 causes the latch 59 to disengage the link 55 and the lever 10 will be reset by the pull of spring 61. When the lever 10 25 moves inwardly it is disposed in position to receive the next inserted coin.

In order that the main lever 38 cannot be actuated without insertion of a coin in chute 2, a 30 latch lever 10 is provided. This is pivotally suspended from a pivot 11 on a bracket 12 attached to the front wall of the housing. At its lower end the latch has a hook 13 to engage a stud 14 fixed in the lever 38. Normally the latch is in holding position, but it is connected by a link 75 35 with the lower end of a vertically disposed lever 76 pivotally mounted at a medial point, as at 77, by a bracket 78 on the chute 2. The upper end of the lever 76 is beveled and when the parts are set to receive a coin, supports thereon the end 40 of lever 10, as shown in Fig. 1. Thus, when a coin is dropped into chute 2 against lever 10, it slightly depresses the latter, and this causes the lever 76 to move pivotally in a manner to pull the latch 78 out of the path of stud 14 so that lever 38 can be 45 depressed.

In order that an operation cannot be partially completed, a ratchet bar 80 is fixed vertically alongside of lever 38 and this has a rack toothed edge 81 formed about pivot 35 as a center, and 50 a pawl 82 is pivoted on the lever to yieldingly engage the teeth, as seen in Fig. 5, in a manner whereby the pawl is released for a return of the lever 38 only at the limits of movement in either direction.

To retard the rotation of the sleeve for the coin 55 testing operation there is provided an air cylinder 90 in which a piston 91 is reciprocally fitted. The piston has a rod 92 connecting it with lever 38, and a back check relief valve 93 is provided 60 in the piston to permit quick downward pull of the lever but a retarded return by reason of limiting the rate of exhaust of air past the valve.

Assuming the parts to be so constructed, the 65 operation is as follows:—

When a coin, token or slug is dropped into the coin chute 2 it passes downwardly therein into contact with the inner end portion of the lever 10, as in Fig. 6. Impact against the lever 10 causes a slight downward movement thereof which rocks 70 the lever 76 in a manner to withdraw the latch 73 from holding contact with the pin 14 on the lever 38. The operator then presses downwardly on the outer end of the lever 38 moving it from the position of Fig. 1 to the position of Fig. 2. By this 75 downward movement, the cable 42 effects the

rotation of sleeve and the winding up of the spring 45 within the sleeve, and during the latter part of the downward movement of the lever 38 the stud 60 causes the bar 50 to be shifted downwardly so that the cam surfaces 50a of the bar 5 move the sleeve 12 inwardly, thereby causing the pad 11 to be pressed tightly against the face of the coin, and the coin moved over against the face of block 16 to depress the feelers 15, as shown in Fig. 2. Then when the lever 38 is released, 10 after being depressed, the spring 45 causes a rotative movement of the sleeve whereby the coin is slowly rotated while held in contact with the feelers 15; the rotary movement of the sleeve being retarded by the controlled movement of the piston 91 in the cylinder 90.

Assuming that the coin is of the particular kind intended for use in the machine, such for example as the buffalo nickel, the irregularities of that surface against which the inner ends of 20 the pins 15 engage will cause the pins to be shifted inwardly or outwardly in accordance with the irregularities and at a certain position of the coin can be made to bring the notches 27 of the several bars 24 into alignment and will permit 25 the lever 28 to drop therein. Dropping of the lever 28 effects movement of the diverting gate 4 to open position, as in Fig. 2. Coincident with the inward movement of the sleeve 12 in gripping the coin, the coin shifts the pin 58 outwardly and 30 through the mediacy of the lever 55 withdraws the lever 10 from the path of the coin so that when it is later released by the pad 11 it will drop down for continued movement in the slot 2. If the coin should not be of the proper character, it is apparent that the bars 24 will not be shifted to bring their slots 27 into alignment, and the lever 28 will not be permitted to drop and the diverting gate 4 will then remain closed, 35 and when the coin is released by the pad it will be 40 delivered into the box 7a.

Assuming that the coin is of the proper kind and that it causes the diverting gate 4 to be opened as in Fig. 2, when it is dropped through chute 2, it will trip the lever 30 and thereby lift 45 the lever 28 and permit resetting of the feelers under pull of springs 21. Passage of the coin through the chute 2 also effects tripping of the lever 63 which releases the latch lever 59 and 50 resets the lever 10.

In the alternative construction, as illustrated in Fig. 9, the block 16a which replaces block 16, as seen in Fig. 1, is provided in its inner face with a depression adapted to seat only selected coin therein. In the block, are circuit contacts 55 94 and 95 terminating flush with the base of the depression and connected at their outer end by wires 96 and 93 in an electric circuit which controls a solenoid 97. The solenoid is so located that when energized it magnetically lifts the 60 lever 28 thereby to actuate the valve 4, as previously described. In this arrangement, it is understood that no circuit can be completed except by a coin that can be seated in the depression of block 16a.

In the other alternative illustrated in Figs. 10 and 11, there is a block 16b rotatably mounted in the bracket 98, and this block has a depression 98a adapted to seat only the intended coin. When a coin is so seated, it operates as a connection between the block 16a and sleeve 12 for rotating the block. On the block 16b is a cam lobe 99 adapted, on rotation of the block, to disengage the lever 28, thus to actuate valve 4 to 70 open position.

Either of these latter devices are subject to modification without departing from the invention.

While I have illustrated the device as being manually operated through the mediacy of the hand lever 38, it is apparent that other forms of mechanisms might be employed for automatic operation under spring or electric power. For instance, the insertion of a coin might be used 10 to close a circuit through electrical equipment for actuating the sleeve 12 or it might be employed to release a spring driven mechanism for rotating the sleeve.

Having thus described my invention, what I 15 claim as new therein and desire to secure by Letters Patent is—

1. In a coin selecting mechanism, in combination, a coin chute, a gate in the chute normally positioned for diverting coins therefrom, means 20 associated with the chute whereby each coin passing therealong will be temporarily checked before reaching the gate, means operable to rotate the coin while checked, feelers arranged to be conjointly actuated by surface irregularities 25 on the same side of the rotated coin to release the gate, normally restrained means for actuating the gate to non-diverting position, and means controlled by said feelers for restraining said last named means.
2. In a coin selecting mechanism, a coin chute, a gate member associated therewith for diverting coins from the chute, a lever connected with the gate to hold it in diverting position, a means for temporarily stopping each coin deposited in 30 the chute, means for rotating the coins when stopped, a plurality of feeler pins mounted to engage with the same side surface of a coin while it is rotated and to be individually moved by the surface irregularities of the coin, and slides normally supporting said lever in a manner whereby the gate is held in diverting position and adapted to be individually moved by said feelers to conjointly effect release of the lever for moving the diverting gate to a non-diverting position.
3. In a coin selecting means, a coin chute, a diverting gate normally disposed in the chute for diverting coins therefrom, a testing device comprising means for stopping a coin in the chute before reaching the gate, means operable to 40 rotate the coin while stopped, a plurality of feelers mounted to engage at different points with the surface of the coin as it is rotated and to be moved by its surface irregularities, a normally restrained lever, means operatively connecting the lever with the diverting gate for moving it to non-diverting position, and means individually actuated by the feelers to conjointly control release of the lever to actuate the valve to non-diverting position.
4. In a coin selecting means, a coin chute, a gate member normally positioned in the chute for diverting coins therefrom, a testing device comprising means for stopping a coin in the chute before reaching the gate, means operable 50 to rotate the coin while stopped, a plurality of feelers mounted to engage at different points with the surface of the coin as it is rotated and to be individually moved by its surface irregularities, a normally restrained lever, means operatively connecting the lever with the diverting gate to move it from diverting to non-diverting position, means individually actuated by the feelers to conjointly effect release of the restrained lever to actuate the gate to non-diverting position, and a lever extended into the 55

chute at a point beyond the diverting gate to be engaged and actuated by a passing coin to reset the gate actuating lever.

5. A coin selecting means comprising, in combination, a coin chute, a gate in the chute for diverting coins therefrom, means for temporarily stopping coins in the chute prior to reaching said gate, means adapted to be manually set in motion to cause the stopped coins to be rotated, feelers arranged to be actuated individually by surface irregularities of a coin being rotated, a pivoted lever, means connecting the gate and lever for actuation of the gate to non-diverting position, slides, corresponding to the several feelers conjointly controlling the lever thereby to retain the gate in position to divert coins from the chute and means connecting each of the slides with its corresponding feeler whereby the slides, when moved by a coin of selected kind, will conjointly effect the release of the lever for 20 actuation of the gate to non-diverting position.

6. A coin selecting means comprising, in combination, a coin chute, a gate in the chute normally positioned for diverting coins therefrom, means for temporarily stopping coins in the chute prior to their reaching said valve, means adapted to be manually set in motion to cause the stopped coins to be rotated, feelers arranged to engage the stopped coin and to be actuated by its surface irregularities, a pivoted lever, means 30 connecting the gate and lever for actuation of the gate by the lever to non-diverting position, a plurality of slides conjointly restraining the lever thereby to retain the gate in diverting position, means connecting each of the slides with a feeler whereby the slides, when brought to proper relationship by a coin of selected kind, will effect the release of the restrained lever for actuation of the gate to non-diverting position, and means having a part extended into the 35 chute at a point beyond the gate operable by a coin in passing to reset the lever and gate.

7. A coin selecting mechanism comprising a coin chute, a gate in the chute normally positioned for diverting coins therefrom, means for 40 temporarily stopping coins deposited in the chute, means movable into frictional contact with a coin while stopped and whereby the coin may be rotated, means manually movable to effect the rotation of said means to rotate the coin, feelers 45 mounted to engage with and to be relatively moved by contact with surface irregularities of the coin as it is rotated, normally restrained means operatively connected with the gate and adapted to be released by said feelers operating 50 conjointly, whereby the gate is actuated to non-diverting position, and means, including a lever extended into the chute at a point beyond the gate and operable by a coin in passing to reset the normally restrained means and move the 55 gate to diverting position.

8. A device, as in claim 7, wherein the said manual means includes a hand lever, and wherein a latch is provided for locking the hand lever against operating movement, and wherein there 60 is other means, operable by the coin stopping means to release the latch.

9. In a coin selecting means, the combination with a coin chute of means for diverting coins from the guide way and operable between diverting and non-diverting positions by means operable under control of the infiguration of an inserted coin; said means including a device for temporarily stopping the coin in the chute, means for rotating the stopped coin, a plurality of feelers 70

- positioned to simultaneously engage the coin as it is rotated and to be moved by the surface irregularities thereof, a slide operatively connected with each feeler for movement thereby, said slides having notches therein adapted to be alined during 5 rotative action of a coin of proper kind, a lever operatively connected with the gate and adapted to drop into said slots when alined, thereby to move the gate to non-diverting position.
10. In a coin selecting mechanism provided with a single intake coin chute, means for interrupting movement of a coin along said chute and for rotating it about an axis extending through the center of its faces, control devices including 15 a plurality of spaced members projecting into displaceable abutment with one face of a coin when rotated by said means; said devices adapted to direct a coin along the chute or from it; said projecting members being spaced and 20 adapted to bear upon the face of a coin while

being rotated at points spaced laterally at predetermined distances from the central axis of said coin; said control devices being operable by a predetermined relative displacement of said projecting members.

11. In a coin selecting mechanism provided with a single intake chute, means for interrupting the travel of the coin along said chute, means for rotating the coin while thus interrupted, means beyond the interrupting means normally positioned for directing a coin from the chute, control devices adapted to change the position of said directing means for permitting the coin to continue along the chute; said control devices including a plurality of feelers in displaceable abutment with surfaces of the rotated coin and operable by predetermined displacement to actuate the control devices.

CHARLES W. MCKEE.
